(57) **CLAIM**

The ornamental design for a magnetic phone holder, as shown and described.

DESCRIPTION

FIG. 1 is a front, left and top perspective view of a first embodiment of a magnetic phone holder showing my new design;

FIG. 2 is a front, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, left and top perspective view of a second embodiment of the magnetic phone holder showing my new design;

FIG. 10 is a front, right and bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front, left and top perspective view of a third embodiment of the magnetic phone holder showing my new design;

FIG. 18 is a front, right and bottom perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof; and,

FIG. 24 is a bottom plan view thereof.

The broken lines in the drawings depict portions of the magnetic phone holder that form no part of the claimed design.

1 Claim, 24 Drawing Sheets
